WEATHERPROOF ROLLER CONSTRUCTION

Walter E. Saxe, Alhambra, Calif., assignor to The Conveyor Company, Los Angeles, Calif., a corporation of California

Application February 13, 1943, Serial No. 475,797

8 Claims. (Cl. 193—37)

My invention relates to rotary devices such as rollers, pulleys, sheaves, and the like, and is directed to the problem of protecting from the weather bearings or other elements in the axial regions of such rotary devices. Without employing any limitation in the scope of my concept or in the fields of usefulness of the invention, I elect to describe my weather-protecting arrangement as incorporated in the construction of an outdoor roller for the return traverse of a conveyor belt. Such a return-traverse roller may be directly exposed to rain or drenched with moisture squeezed from a water-soaked conveyor belt.

It is a feature of the invention that it meets effectively the requirements of large conveyor systems employed for large scale construction projects such as dams. The object of my invention is to satisfy such requirements. The prime requisite, of course, is effective protection against moisture, but also essential are ruggedness, simplicity, inexpensive construction, and suitable merging with the usual and necessary elements for mounting and supporting a conveyor roller.

It is a special object of my invention to provide a simple weather-protecting arrangement that is completely exposed to view and may be adequately inspected at a glance. A further object is to provide a weatherproof construction in which a bearing packed with water-soluble lubricant may be incorporated for prolonged use without replenishment, service periods of more than a year being contemplated even under the most severe conditions. A still further object is to provide a roller construction in which the means for rotatably supporting the roller cooperates in protecting the axial region of the roller from the weather.

The above and other objects and advantages of my invention will be apparent from my following description, taken with the accompanying drawing.

In the drawing which is to be regarded as merely illustrative only,

Fig. 1 is an end elevation of a conveyor roller embodying my invention, the roller being supported by a hanger;

Fig. 2 is a longitudinal section at one end of the roller taken as indicated by the line 2—2 of Fig. 1;

Fig. 3 is chiefly a longitudinal section of a casting employed at one end of the roller;

Fig. 4 is an elevation of the casting as viewed from the inner end; and

Fig. 5 is a cross section taken as indicated by the line 5—5 of Fig. 3.

A horizontally positioned conveyor roller generally designated 10 is mounted on a fixed non-rotating hexagonal shaft 11 that is shown supported by a hanger 12 from an overhead support. The roller 10 has a concave end wall 13 that is shaped to form a central cylindrical recess 15. The outer roller portion of an anti-friction bearing 16 is seated in the end recess 15, while the inner portion of the bearing is fixedly mounted on the hexagonal shaft 11. At the other end of the roller 10 (not shown) is a second support means for the shaft 11 and a second bearing similar to the bearing 16.

The present invention comprises an outwardly extending annular flange 17 on the end wall 13 concentric to the roller axis together with a shield generally designated 18. Preferably, but not necessarily, the shield 18 is integral with a body or special casting 20 mounted in the hanger 12 to engage and support the end of the hexagonal shaft 11.

The annular flange 17 may be simply a collar welded onto the concave end wall 13 but, by preference, I employ a collar such that the inner annular surface 21 of the collar is flared outwardly with respect to the roller axis. Thus the drawing shows a collar fabricated from sheet metal or steel plate, the collar being welded onto the end wall 13 of the roller. Such a collar made of sheet material provides not only the flared inner surface 21 but also a flared outer surface 22.

If the roller is stationary while exposed to rain, moisture falling on the upper side of the annular flange 17 and impinging on the end wall 13 of the roller above the annular flange will be diverted from the inner circular space 23 defined by the flange. It is readily apparent in Fig. 1 that when the roller 10 is stationary, the annular flange 17 together with the end wall 13 forms a drainage channel 25 of V-shaped cross section, and it is further apparent that any moisture on the upper surface of the annular flange will drain into this channel. When the roller 10 is rotating, liquid on the outer surface 22 of the annular flange 17 tends to flow by centrifugal action to the rim of the flange and is discharged centrifugally from the rim. As for the inner surface 21 of the flange 17, it is apparent that any moisture that might conceivably enter the circular space 23 to fall on the lower portion of the annular flange will drain toward the rim of the flange if the roller is stationary and will flow centrifugally to the rim if the roller is rotating.

The casting 20 may be formed with a peripheral recess or groove 26 extending around the sides

and bottom of the casting for engagement with a complementary cradle 27 formed in the hanger 12. By virtue of such an arrangement the casting 20 may be removably mounted on the hanger and yet be rigid with respect to the hanger. The casting 20 is formed with a blind hexagonal socket 28 to receive the end of the hexagonal shaft 11, and a suitable set-screw 30 may be employed to insure retention of the shaft. It is contemplated that the set-screw will fit relatively snugly in its bore and will be coated with a suitable water-resisting material such as heavy non-water-soluble grease so that the socket 28 will be wholly waterproof.

The shield 18 integral with the casting 20 may take various forms to complete the protection of the circular space 23 against falling moisture. In the preferred practice of my invention the shield 18 is in the form of a wall extending upwardly into the annular space so that the annular flange 17 overhangs the upper edge 31 of the wall. The drawing shows the shield to be an inwardly inclined wall of sufficient extent laterally and vertically to adequately mask the circular space 23 from above, the lower portion of the shield being spaced outward from the circular space for drainage diversion. By making at least the upper edge 31 curved to conform with the annular configuration of the flange 17, I am able to place the upper edge 31 sufficiently close to the inner surface 21 of the annular flange to preclude the possibility of moisture reaching the axial regions of the roller. The particular shield configuration shown, with the shield extending well into the circular space 23, makes it unnecessary to extend the shield below the level of the roller axis. Leaving the lower half of the circular space 23 open reveals the bearing 16 for inspection without exposing the bearing to rain.

There is necessarily a gap between the sides of the shield 18 and the adjacent portions of the surrounding annular flange 17, but no moisture can fall vertically into the circular space 23. Any rain falling in an inwardly inclined direction would be completely blocked by the shield 18 from the upper half of the circular space 23 and most of the lower half. Any moisture that falls within the lower half of the circular space from an inclined direction impinges on the lower portion of the inner annular surface 21 and then readily drains outwardly away from the circular space either by gravity or by centrifugal force, as heretofore noted.

The present arrangement is highly efficient even in the face of rain driven inward toward the end of the roller at a relatively low angle. Thus the hanger 12 is in the form of a relatively extensive wall serving as a curtain wider than the diameter of the annular flange 17 and extending below the axis of the roller 10 substantially to the lowest level of the annular flange 17. The hanger is cut away to provide a window 32 for admission of the casting 20, but the shield 18 is positioned to intercept any rain falling inward through this window. Thus the shield 18 is complementary to the hanger 12 in that the shield stops any rain falling through the hanger opening, and the hanger stops any rain that might otherwise be driven toward the roller 10 below the shield.

It is to be further noted that there is what may be termed a tapering clearance between the shield 18 and the end wall 13 of the roller. Thus, Fig. 2 shows the rim of the shield 18 inclined away from the end wall 13 so that the clearance be-

tween the two is at a minimum at the top of the shield and increases progressively both ways from the top. Any solid particle falling in the clearance space will not tend to wedge between the shield and roller, since the rotation of the roller will tend to carry the particle in a direction of increasing clearance.

The preferred form of my invention described in detail herein will suggest to those skilled in the art various changes and substitutions under my basic concept; I reserve the right to all such departures from my description that properly lie within the scope of my appended claims.

I claim as my invention:

1. Means for protecting against falling moisture the axial region at the outer end of a roller and the like, comprising: an outwardly extending annular flange on the end of the roller; and a fixed shield extending upwardly into the circular space defined by said annular flange, the annular flange overhanging the upper edge of said shield to prevent falling moisture from dropping inside said upper edge, said shield masking said space, and said shield being so formed that the clearance between said shield and the roller is relatively small at the upper edge of said shield and increases progressively downwardly therefrom, whereby solids between said shield and said flange are removed by rotation of said flange.

2. In means for protecting from falling moisture the region of a shaft on which a roller or the like is rotatably mounted, the combination of: an outwardly extending annular flange on the end of the roller, the inner surface of said annular flange being of flaring configuration so that moisture thereon tends to gravitate to the rim of the flange when the roller is stationary; a support wall spaced from the end of the roller to serve as a curtain for intercepting driving rain directed toward the circular space defined by said flange, said wall having an opening forming a support seat and an open window above the seat; a body normally resting in said seat, said body being movable through said window into and out of said seat, said body having a blind socket encasing the end of said shaft; and a shielding wall integral with said body having a curved upper edge extending into the circular space defined by the annular flange, the annular flange overhanging said curved upper edge of said shielding wall to prevent moisture from dropping inside said upper edge, said shielding wall being positioned relative to said window to intercept rain driven through the window toward said circular space.

3. In means for protecting from falling moisture the region of a shaft on which a roller or the like is rotatably mounted, the combination of: an outwardly extending annular flange on the end of the roller; a support wall spaced from the end of the roller to serve as a curtain for intercepting rain directed toward the circular space defined by said flange, said wall having an opening forming a support seat and a window above the seat; a body normally resting in said seat, said body being movable through said window into said seat, said body supporting said shaft; and a shielding wall associated with said body and extending into the circular space defined by the annular flange, the annular flange overhanging the upper edge of said shielding wall to prevent moisture from dropping inside said upper edge.

4. In means for protecting from falling moisture the region of a shaft on which a roller or

the like is rotatably mounted, the combination of: an outwardly extending annular flange on the end of the roller, the inner surface of said annular flange being of flaring configuration so that moisture thereon tends to gravitate to the rim of the flange when the roller is stationary and tends to travel centrifugally to the rim of the flange when the roller is rotating; a support wall spaced from the end of the roller to serve as a curtain for intercepting rain directed toward the circular space defined by said flange, said wall having an opening forming a support seat and a window above the seat; a body normally resting in said seat, said body being movable through said window into said seat, said body supporting said shaft; and a shielding wall associated with said body and extending into the circular space defined by the annular flange, said shielding wall being positioned relative to said window to intercept rain driven through the window toward said circular space.

5. In means for protecting from falling moisture the region of a shaft on which a roller or the like is rotatably mounted, the combination of: an outwardly extending annular flange on the end of the roller; a support wall spaced from the end of the roller to serve as a curtain for intercepting rain directed toward the circular space defined by said flange, said wall having an associated support seat and a window above the seat; a body normally resting in said seat, said body being movable through said window into said seat, said body supporting said shaft; and a shielding wall associated with said body and extending into the circular space defined by the annular flange, said shielding wall being positioned relative to said window to intercept rain passing through the window toward said circular space.

6. In means for protecting from falling moisture the region of a shaft on which a roller or the like is rotatably mounted, the combination of: an outwardly extending annular flange on

the end of the roller; a support wall spaced from the end of the roller to serve as a curtain for intercepting rain directed toward the circular space defined by said flange, said wall having an associated support seat and a window above the seat; a body normally resting in said seat, said body being movable through said window into said seat, said body supporting said shaft; and a shielding wall associated with said body and extending into the circular space defined by the annular flange.

7. In means for protecting from falling moisture the region of a shaft on which a roller or the like is rotatably mounted, the combination of: an outwardly extending annular flange on the end of the roller; and a support wall spaced from the end of the roller to serve as a curtain for intercepting rain directed toward the circular space defined by said flange, said wall having an associated support seat and a window above the seat; a body normally resting in said seat, said body being movable through said window into said seat, said body supporting said shaft; and a shielding wall associated with said body and extending into the circular space defined by the annular flange.

8. In means for protecting against falling

moisture the region of a shaft on which a roller or the like is carried for rotation, the combination of: an outwardly extending annular flange for the end of said roller; a support for said shaft and spaced from the position of the end of said roller; and a fixed shield associated with said support and extending upwardly into the circular space defined by said annular flange, the annular flange overhanging the upper edge of said shield to prevent falling moisture from dropping inside said upper edge, and said shield being so formed that the clearance between said shield and said roller position is relatively small at the upper edge of said shield and increases progressively downward therefrom, whereby solids between said shield and said flange are removed by rotation of said flange.
